UNITED STATES PATENT OFFICE.

GEORGE GRAHAM AND ADOLPH C. HELMUS, OF DOUGLASTON, NEW YORK.

FABRIC-ROLL HOLDER.

Application filed February 10, 1926. Serial No. 87,365.

The present invention relates to improvements in fabric-roll holders, that is to say to forms or frames upon which fabrics are wound for storage purposes.

5 In stores where cloth or fabrics are sold in the piece or in smaller quantities, the bolts are arranged in stacks. The purchasers frequently ask for small samples, and it has been a general practice heretofore, for this purpose, to remove the bolts from the stacks and cut small samples from the free ends of the fabrics. Quite some work is involved in this operation due to the fact that the required bolts may be located at or near the 10 bottom of the stack. On the other hand, the furnishing of samples results in considerable loss to the merchant because that part of the free end of the cloth bolt from which the sample has been cut cannot be charged to 15 a customer, it being mutilated, attention being called to the fact that usually a sample of a few inches in width and length is cut from the free end of the cloth bolt, the length of the sample not extending through- 20 out the width of the cloth.

The main object of the present invention is to provide a casing-like form or cloth holder, in which is slidably disposed a small receptacle, adapted to contain small samples 30 of the cloth or fabric wound upon the said form, said receptacle being adapted to be withdrawn from the form or holder, thereby enabling the attendant to furnish samples to the purchaser.

35 Another object of the invention is to provide a form or fabric holder of the character described which is simple in construction, efficient in operation, durable in use and capable of manufacture on a commercial 40 scale, or in other words one which is not so difficult to make as to be beyond the reasonable cost of such a contrivance.

With these and other objects in view, which will more fully appear as the nature 45 of the invention is better understood, the same consists in the combination, arrangement and construction of parts hereinafter described, pointed out in the appended claims and illustrated in the accompanying 50 drawings, it being understood that many changes may be made in the size and proportion of the several parts and details of construction within the scope of the appended claims, without departing from the 55 spirit or sacrificing any of the advantages of the invention.

One of the many possible embodiments of the invention is illustrated in the accompanying drawings, in which:—

Figure 1 is a top plan view of a fabric holder constructed in accordance with the present invention, part of its covering being broken away in order to more clearly show the interior construction; Fig. 2 is an end view thereof, showing the fabric wound thereon in dotted lines; Fig. 3 is a section taken on line 3—3 of Fig. 1, on a larger scale; Fig. 4 is a section taken on line 4—4 of Fig. 1, also on a larger scale; and Fig. 5 is a top plan view, on a larger scale, of one 60 of the corners of the holder.

The form or holder comprises an oblong frame, including two longitudinal members 10, united at their ends by two transverse members 11 and 12. Transverse stays or 65 braces 13 connect the longitudinal members, intermediate their ends. The longitudinal members 10 and the transverse members 11 and 13 are, preferably, made of wood, while the transverse member 12 is, preferably, 70 made of metal, although this is not essential. The transverse member 12 is, in the case illustrated, in the form of a shell, including an end wall 14 and a continuous 75 side wall 15, into which one end of each longitudinal member 10 is fitted. The elements so far described may be united in any suitable manner, thereby forming an oblong 80 frame. This frame is provided with a bottom member 16 and a top member 17, preferably, made of cardboard, and the entire 85 frame may be covered with some suitable fabric or paper, denoted by the numeral 18, to give the form or holder a finished appearance. As appears from the foregoing, the 90 form or holder constitutes a casing, the longitudinal edges of which are rounded, as shown at 19, to permit of a proper winding of the cloth or fabric thereon.

In the end wall 14 of the shell above referred to is provided an oblong opening 20, through which is adapted to be inserted into the form or holder a receptacle or drawer 21, comprising a front wall 22, adapted to lie in the plane of the end wall 14 of the 100 transverse member 12, a side wall 23, extending at right angles to the front wall 22, and an arc-shaped side wall 24, connecting the front wall 22 and the side wall 23, all of said walls rising from a bottom 25. The drawer 105 is fixed by a pivot pin 26 to the transverse member 12, where the latter joins one of 110

the longitudinal members 10 of the frame. On the front wall 22 of the drawer is provided a knob 27, by which the said drawer may be swung around its pivot pin 26. At 5 the junction point of the side walls 23 and 24 of the drawer is provided an upwardly extending projection 28, which abuts against the inner face of the end wall 14 of the transverse member 12 when the drawer is shifted 10 from the position shown in full lines in Fig. 1 of the drawings into the position shown in dotted lines in said figure, thereby limiting the outward movement of the drawer.

As appears from Fig. 2 of the drawings, 15 the cloth or fabric 29 may be wound upon and unwound from the form or holder without interfering with the operation of the drawer 21. Into the drawer are placed small samples of the cloth or fabric wound 20 upon the form or holder. The cloth bolts are stacked in a manner that convenient access can be had to the said drawers, so that, when a sample is to be removed from a 25 drawer in any one of the forms or holders, this can be done without removing the bolt of cloth from the stack. Should a purchaser desire to examine the cloth, the respective bolt is removed from the stack for this purpose. A sample can then be withdrawn by 30 taking hold of the knob 27 on the drawer and shifting the latter around the pivot pin 26 into the position shown in dotted lines in Fig. 1 of the drawings, whereby access can be had to the samples in said drawer. After 35 the sample has been removed, the drawer is shifted into the position shown in full lines

in Fig. 1 of the drawings, in which the side wall 23 of the drawer abuts against one of the longitudinal frame members 10.

What we claim is:

1. A cloth form comprising an oblong casing-shaped frame provided in one of its end walls with an opening, a drawer adapted to be inserted through said opening into said frame including a bottom from which rises 45 a flat front wall, a flat side wall extending at right angles to said flat front wall, and an arc-shaped side wall connecting said flat front wall and said flat side wall, a pivot pin extending through said drawer into said 50 casing-shaped frame, said pivot pin being disposed at the junction point of said flat front wall and said flat side wall adjacent to the opening in said casing-shaped frame, said drawer being adapted to be swung 55 around said pivot pin and thereby adapted to be inserted into and to be withdrawn from said frame.

2. A cloth form according to claim 1, comprising an upwardly extending projection 60 on said drawer at the junction point of the side walls thereof, said projection being adapted to abut against that end wall of said casing-shaped frame in which the opening is provided, thereby limiting the outward movement of said drawer.

Signed at New York, in the county of New York, and State of New York, this 4th day of February, A. D. 1926.

GEORGE GRAHAM.
ADOLPH C. HELMUS.
